United States Patent Office

Des. 203,167
Patented Dec. 14, 1965

203,167

CHAIR FRAME

Ronald Beckman, New York, N.Y., and Rodney Y. Hatanaka, Montreal, Quebec, Canada, assignors to Herman Miller, Inc., Zeeland, Mich., a corporation of Michigan

Filed Jan. 25, 1963, Ser. No. 73,311

Term of patent 14 years

(Cl. D15—1)

FIG. 1.

FIG. 2.

FIG. 3.

FIG. 4.

FIG. 1 is a perspective back view of one embodiment of the chair frame of this invention;

FIG. 2 is a front perspective of the chair frame shown in FIG. 1;

FIG. 3 is a plan view of the chair frame shown in FIG. 1; and

FIG. 4 is a side elevation of the chair frame shown in FIG. 1.

We claim:

The ornamental design for a chair frame, substantially as shown.
